CLOTHES LINE AND DRIER

Application filed April 26, 1929. Serial No. 358,388.

This invention relates to a class of devices adapted to be used for permitting articles to be suspended from elevations. Our invention has as its object primarily to provide a simple and efficient device or line whereby articles when washed may be dried, and whereby articles may be aired by being suspended outside the building and especially at high elevations, and is of such form that articles may be hung on the entire length of the line and also permits any articles to be removed therefrom without removing the other articles which may be on the line, and all this is done in a manner which does not endanger the person performing this work as our invention provides for one of the supporting members of the line to be fastened across the window or structure from which it is operated and thus enables the user of the device to stand in an erect position on the inside of the open window or structure while placing articles on the line or while pulling the line around. Another object concerns the use of a plurality of suspended pulleys so arranged as to permit much greater clothes-line space in a given distance between the supports holding the clothes-line than has heretofore been possible. Our invention consists essentially of a belt member from which a clothes-line is suspended by rods or spacers, the belt moving about a plurality of laterally suspended pulleys, such as to permit the use of the full clothes-line, and the pulleys are so mounted as to operate in a lateral plane and to permit the tightening or loosening of the belt and clothes-line by freely adjustable and laterally freely suspended pulleys which are suspended from and adjacent to an adjusting means attached to the support fastened to the window or other openings in a building or to other parts of any structure, especially at elevated heights, all of which adjusting can be done without causing the user to endanger himself as it permits the user or operator to stand in an erect position inside the window, opening or place of operation to tighten or loosen the belt and clothes-line by means of one of the specially constructed features of our invention which

is in the form of movable arms lying in the same plane and from which a plurality of pulleys are suspended, and the adjusting device or means is so designed that it is fastened to the window, opening or structure 55 from which the clothes-line is operated or adjusted.

A practical embodiment of our invention is represented in the accompanying drawing, which forms part of this specification, 60 in which similar characters of reference indicate corresponding parts in all the views and will be pointed out in the claims attached hereto.

In the drawing, Figure 1 is a composite 65 plan and side elevation view of our device, showing the belt and the clothes-line, embodied in our invention, fragmented.

Fig. 2 is a fragmented view of the belt and clothes-line showing the manner in 70 which articles are hung on the clothes-line.

Fig. 3 is a top and side elevation view of the type of pulleys used in Fig. 1.

The device or adjustably supported clothes-line has two rigidly fixed supports 75 2 and 11. Support 2 which is a bracket or of the bracket type is fastened to a pole or similar support, being fastened thereto by means of the bracket 2 which is tightened by means of bolt and nut 1. Support 11 is fastened to a window frame or to any other rigid structure, from which the device is used or operated, by means of bolts or screws which are inserted through holes 13 cut in support 11, and fastened to the window 85 frame or other rigid structures of like nature.

Arms 3 are rigidly bolted together at one end on to lip 23 of bracket 2 by means of bolt and nut 20, one arm being lapped on the other at this position of fastening. Arms 3 are further secured so as to prevent lateral motion in opposite directions from each other by means of cross-member 4 which is 90 bolted to arms 3 by bolts and nuts 21. Arms 22 are adjustably supported by bolt 14 such that bolt 14 acts as a pivot and permits arms 22 to move laterally and in the same plane. Arms 3 and 22 are so attached to supports 100

2 and 11, respectively as to make arms 3 and 22 lie laterally and in the same plane.

Eye bolts 10 which are each threaded at one end are fastened to arms 22 by bolts 5 and nuts 15, the bolts 15 passing through the eyes of eye bolts 10 such as to permit eye bolts 10 to pivot about bolts 15. The threaded ends of eye bolts 10 are inserted in slots 16, which are cut in support 11, the 10 eye bolts being secured to support 11 by means of wing nuts 12 which screw on to the threaded ends of eye bolts 10. Slots 16 are cut wide so as to permit free lateral movement of eye bolts 10 which are inserted 15 in the slots. However, the vertical depth of slot 16 is cut so as to allow just sufficient clearance as will permit the threaded end of eye bolts 10 to slip freely into the slots 16, but will not permit free vertical motion.

20 By means of eye bolts 10 which are pivotally attached to arms 22 by bolts 15, the arms 22 may be laterally adjusted in either direction by taking up on or loosening wing bolts 12. Slots 16 are cut broad so as to 25 permit eye bolts 10 to adjust themselves when wing nuts 12 are taken up on or loosened in the course of adjusting arms 22.

From arms 3 and 22 are suspended pulleys 8 by means of spindles 7 which spindles are 30 rigidly secured to arms 3 and 22 and pass through the centers and attached to pulleys 8 such as to allow free rotation of pulleys 8 on spindles 7. Pulleys 8 are of the drum type and have a broad beveled base. The 35 pulleys 8 suspended by means of spindles 7 from arms 3 rotate laterally and in a fixed position. Pulleys 8 suspended by means of spindles 7 from arms 22 are freely suspended and oppositely disposed from pulleys 8 40 which are suspended from arms 3. Pulleys 8 suspended from arms 22 may work in varied positions in a lateral plane by adjusting the pivoted arms 22 which are free to move in a lateral plane.

45 Belt member 6 which is of the endless type of line, rope or cable is supported on and rotates around pulleys 8. The clothes-line 5, which is also of the endless type of line, rope or cable, is attached to and spaced or 50 suspended from belt 6 by means of spacer rods 9 which are rigidly attached to both belt 6 and clothes-line 5. Thus as belt 5 is rotated about pulleys 8, the belt carries with it clothes-line 6, in such manner as to keep clothes-line 6 free of pulleys 8, this being 55 accomplished by means of the spacer rods which are sufficiently long to keep the clothes-line free of and away from the pulleys on which belt 6 is supported and about 60 which it rotates. The belt member 6 and clothes-line 5 are adapted to be manually moved back and forth as desired. Any slack which may occur in belt 6 and clothes-line 5 can be taken up by taking up on eye 65 bolts 10 with wing nuts 12 which through

means of eye bolts 10 spread arms 22 which in turn separate pulleys 8 which are suspended from arms 22 by means of spindles 7. As the pulleys separate, the belt 6 is drawn tighter which effect is likewise transmitted to clothes-line 5 by means of the spacer rods 9. Similarly, too great a strain on belt 6 and clothes-line 5 may be relieved by loosening up on wing nuts 12 which will permit arms 22 to be forced together as 75 long as there is sufficient tension in belt 6 and clothes-line 5.

To operate the device, the belt member 6 is manually swung in the desired direction back and forth by merely reaching the arm out of the window, opening or from place of operation, and moving the spacer rods in the direction in which it is desired to rotate the belt. During the rotation of the belt member, clothes and other articles as 18 may be suspended at intervals from clothes-line 5, which rotates simultaneously with the belt member, by means of commonly used clothes-pins as 17 or the like. Thus, we provide a simple and efficient clothes-line 80 whereby various articles may be exposed to the air at high elevations without requiring the person using the clothes-line to risk the danger of leaning out of the window, or other opening of the building or 85 other structure on which the device is operated or used.

In the foregoing description we have embodied the preferred form of our invention, but we do not wish to be understood as limiting ourselves thereto, as we are aware that modifications may be made therein without departing from principle or sacrificing any advantages of this invention, therefore we reserve to ourselves the right to make such changes as fairly fall within the scope 90 thereof.

Having thus described our invention, we claim as new and desire to secure by Letters Patent:—

1. In a device of the character described, a supporting member, a pulley supported thereby, a second supporting member, levers pivoted thereto, a pulley at the free end of each lever, means adjustably positioning the levers laterally of a straight line joining the supporting members, and a line trained about the said pulleys.

2. An adjusting means for a clothes line comprising a supporting member, divergent lever arms pivoted thereto, a pulley on each lever arm eccentric to the pivotal mounting thereof, and means connecting the lever arms with the supporting member for adjusting the position of the said lever arms.

3. An adjusting means for a clothes line comprising a supporting member, lever arms pivoted thereto to swing in the same plane, a pulley at the free end of each lever arm, and means connecting the said lever arms

and supporting member for independently adjusting each lever arm.

4. In a device of the character described, a supporting member comprising an elongated bar, divergent lever arms co-axially pivoted thereto, a pulley at the free end of each lever arm, means intermediately connecting each lever arm and the supporting member for adjusting the position of each lever arm, said adjusting means comprising a bolt pivotally attached to each lever arm, said bolt extending through the supporting member, and means to secure the bolt in position.

15 In testimony whereof, we have hereunto subscribed our names.

HERBERT THOMAS HORSCRAFT.
WILLIS LEROY KING.
